LIGHT UNIT

Willis A. Pennow, Cleveland, Ohio, assignor to Westinghouse Electric Corporation, East Pittsburgh, Pa., a corporation of Pennsylvania

Original application August 7, 1947, Serial No. 767,137. Divided and this application August 31, 1954, Serial No. 453,246

11 Claims. (Cl. 340—25)

My invention relates, generally, to lighting equipment, and, more particularly, to lighting equipment for use as an aid in landing aircraft.

Due to the increase in air traffic in recent years, there has been an increasing demand for apparatus whereby an aircraft may be landed during adverse weather conditions. With such apparatus, it is obvious that the landing delays and detained flights, etc. would be minimized. Heretofore, lighting units for such purposes have been limited to moderate energy consumption, whereby the brightness output of the unit is limited. Some of such prior units have been limited in brightness by the size of the capacitor and the voltage output of the wiring means. In many approach lighting systems, it is also highly desirable to be able to flash the light units in a predetermined manner which may be varied as the weather conditions change. Some prior units have provided means for selectively obtaining such flashing, but have not provided any means whereby the intensity of the flash may be varied. Such units which have been flashed have also required an extensive control system which is not adapted to be used in a large multiple unit installation in view of the cost of the control system. Nor have such units been adapted to be flashed at different intensities in view of the additional wiring costs that would be required.

Accordingly, one object of my invention is to provide a new and improved airport approach lighting unit.

Another object of my invention is to provide a new and improved lighting unit which may be operated continuously or at various selectable intensities.

Another object of my invention is to provide a new and improved lighting unit which may be flashed at various selectable intensities.

Still another object of my invention is to provide a new and improved lighting unit which is adapted to be used with a number of other units, all of which are adapted to be energized from a single source of power.

A further object of my invention is to provide a new and improved airport lighting unit which is provided with an individual power unit within the housing of the unit.

These and other objects of my invention will become more apparent upon consideration of the following detailed description of a preferred embodiment thereof when taken in connection with the attached drawings, in which:

Figure 1 is a substantially central vertical cross-sectional view of one type of lighting unit constructed in accordance with the principles of my invention with the wiring removed and with portions shown in elevation;

Fig. 2 is a substantially central vertical cross-sectional view of another type of lighting unit constructed in accordance with the principles of my invention;

Fig. 3 is a reduced front elevational view of the lighting unit shown in Fig. 1 with the front door removed therefrom;

Fig. 4 is a wiring diagram for the lighting unit as shown in Fig. 1;

Fig. 5 is a reduced front elevational view of the light-

2

ing unit shown in Fig. 2 with the front door removed therefrom; and

Fig. 6 is a wiring diagram of the lighting unit shown in Fig. 2.

As has been indicated, the lighting units constructed in accordance with the principles of my invention are particularly adapted for use in airplane approach lighting systems as is more fully described and claimed in my co-pending application, Serial No. 767,137, filed August 7, 1947, now issued as Patent No. 2,734,180, on an Approach Light System, which has been assigned to the same assignee as this invention, and of which this application is a division. It is obvious, however, that these units are equally suitable for other types of applications, wherein a high degree of control of high intensity light is desired.

Primarily, it will be noted from the drawings that there are two basic types of lighting units constructed in accordance with the principles of my invention, which, for convenience in discussion, will be referred to as flash and blaze units. The unit and wiring diagram relating to a flash unit is shown in Figs. 1, 3 and 4, and the unit and wiring diagram relating to a blaze unit is shown in Figs. 2, 5 and 6. Such terminology is for convenience in describing the units and should not be considered as limiting; particularly so, in view of the fact that the blaze unit may be utilized to operate as a flashing unit.

Referring to Fig. 1, it will be noted that the flash unit comprises an open-ended housing 2 having an approximately rectangular cross-section which is provided with an integral downwardly extending conical shaped base 3 whereby housing 2 may be supported by means of a ball joint 8. Housing 2 may be made from a variety of materials having sufficient mechanical strength and is preferably formed from a material, which, in view of the size, may easily be cast to the desired shape. In view of the excellent resistance to corrosion and light weight, housing 2 is preferably formed from an aluminum casting alloy as is commercially available. Each open end of housing 2 is provided with an integral lip 4 around its periphery. An approximately square door 5, which may be formed from a similar material as housing 2, is secured to each open end of housing 2 in order to form an enclosed housing 2. Each door 5 and 5' may be secured to housing 2 in any suitable manner, and as shown, such manner of mounting comprises a hinge pin 23 which extends along the meeting edge of the doors 5 and 5' and housing 2 at one side of doors 5 and 5' and to which is secured a pair of mating hinge plates 22 at each of its ends. One of each pair of hinge plates 22 is secured to doors 5 and 5', and the other hinge plate 22 of each pair is secured to the housing 2 so that plates 22 may rotate over the hinge pin 23 in the well known hinge manner. In order to provide means for locking doors 5 and 5' to housing 2 at the opposite side of each door 5 and 5' and housing 2 from the hinge pin 23, a hasp 24 and a plate 240 are secured to the doors 5 and 5' and housing 2, respectively, in any suitable manner such as by riveting. Plate 240 extends through its cooperating hasp 24 and is provided with an opening 242 at its outer end through

which the keeper arm of a padlock 6 may be inserted whereby unauthorized access to the housing 2 may be prevented. To further help secure each door 5 and 5' to housing 2, a plurality of overcenter spring latches 28, which are pivotally mounted on housing 2, may be provided to engage a plurality of oppositely located latch hooks 21 secured to doors 5 and 5' which operate in the well known latch manner to hold the doors 5 and 5' securely to the housing 2. Inasmuch as such latch, hinge and hasp constructions are well known in the art, and do not form a part of our invention, it is not believed necessary to more particularly point out their construction or operation. Doors 5 and 5' are also provided with an inte-

gral flange 7 around their inner periphery in which a gasket 32 of any suitable material, such as rubber, may be located, so as to make doors 5 and 5' weathertight with respect to housing 2 in conjunction with flange 4 on housing 2.

As also shown in Fig. 1, ball joint 8 is displaced toward one end of housing 2 which, for the sake of convenience, is referred to as the back of housing 2. As more clearly explained hereinafter, a power unit 200 is located in the back part of housing 2, and, accordingly, the door 5' at the back of housing 2 is solid in order to prevent accidental access to power unit 200. The other door 5 at the front of housing 2 is provided with a central, approximately square opening 9 which is covered by a lens 10 in order that light rays emitting from within housing 2, as hereinafter described, may be transmitted through lens 10. Lens 10 is located immediately behind the opening 9 and is secured to the door 5 by any suitable means, such as by providing a plurality of inwardly projecting lugs 11, integral with door 5 adjacent lens 10, upon which are located clips 12 which engage the inner surface of lens 10. Clips 12 are held in this position by any suitable means, such as machine screws 13, which pass through clips 12 and engage threaded openings in lugs 11. If desired, in order to obtain a weathertight construction between the lens 10 and the opening 9, a gasket 14 of any suitable material, such as neoprene or rubber, may be located between the inner surface of door 5 around the periphery of opening 9 and the outward facing side of lens 10.

In an approach lighting system, it is quite desirable that the lighting units may be movably supported in order that the light rays emanating therefrom may be directed as desired. In order to accomplish this purpose, a variety of movable supporting constructions may be employed. As shown, however, a ball joint 8 is employed which comprises a hollow ball member 15 which may be made of any suitable material, such as aluminum, for the same reasons as given with regard to housing 2, and which is provided with a separate outwardly extending flange member 16 fixed thereto below its horizontal center line. It will be noted that ball member 15 is cut off at both its top and bottom in order to provide a wiring channel therethrough, and that its lower end is provided with an integral downwardly extending hollow stem 17. Stem 17, in turn, may be of any desired length and may be secured in any suitable manner (not shown) to a stationary support (not shown) for the lighting unit. Base 3 of housing 2 is provided with an opening 18 which is formed to provide a spherical socket accommodating the outer surface of ball member 15 which permits ball member 15 to be moved in relation thereto. In order to definitely position ball member 15 to base 3, the flange member 16 is provided with a plurality of openings through which extend machine bolts 19 which threadedly engage openings in threaded openings in the base 3 adjacent opening 18. It is obvious that the relative position of ball member 15 to base 3, and, accordingly, housing 2 may easily be varied by loosening the bolts 19 and moving housing 2 to the desired position, then clamping ball member 15 between base 3 and flange member 16 with bolts 19.

As can be appreciated in large units of this type, doors 5 and 5' are somewhat bulky, and in order to prevent doors 5 and 5' from swinging closed after being opened, the upper inner surface of housing 2 is provided with an integral pair of bosses 25 adjacent the lips 4 respectively. Bosses 25 are provided with integral downwardly extending guide plates 26 having an opening 27 therein through which a guide rod 28 extends. The inner end of guide rod 28 is provided with an offset 29 and a catch 30, so that when the guide rod 28 is moved outwardly from the housing 2 by the opening of door 5, the rod 28 will ride on the lower edge of opening 27 until catch 30 engages the guide plate 26. As offset 29 will then engage the outer side of opening 27, any movement of door 5 in the reverse direction will cause offset 29 to engage the outer side of

plate 26 to prevent accidental closing of door 5. To close door 5, rod 28 need only be lifted above the side of opening 27, so that offset 29 clears the opening 27. In order that guide rod 28 may be activated by opening of the door 5, its outer end is flattened and secured to the inner surface of door 5 by any suitable means, such as a machine screw 33 engaging an integral boss on the inner surface of door 5.

The flash unit is also provided with a dish-shaped reflector 36 which may be made from any suitable material, such as aluminum, or aluminum alloy, which may be provided with a smooth reflecting surface, and which is located within the housing 2 behind the lens 10. The outer edge of reflector 36 is provided with a small outwardly projecting flat flange 41 which is secured at various points around its outer edge by means of machine screws (not shown) extending therethrough and engaging threaded openings in lugs 38 integral with housing 2 which project inwardly thereof behind flange 41. Housing 2 is also provided with an integral lug 39 which extends downwardly from the upper inner surface and to which is secured by any suitable means, such as machine bolts, a downwardly extending supporting plate 37. Plate 37 which is formed from any suitable insulating material such as a phenolic material is located in engagement with the vertex or reflector 36 and is secured thereto by any suitable means such as bolt 42 extending therethrough.

Although such a lighting unit may employ any one of various types of discharge devices, in order to obtain

30 a high intensity light output, a krypton light 43 is preferably employed which is located within reflector 36 so as to obtain the maximum light output from the lamp 43. Such lamps 43 are provided with a main terminal at each of their ends, each of which is adapted to be 35 energized and supported by a socket type lampholder 44. It will be noted, however, that the lampholder 44 next to the vertex of reflector 36, may be supported against the inner surface of reflector 36 by means of the bolt 42, while the opposite lampholder 44 is supported by means 40 of a spring biased horizontally movable L-shaped support 45 to which it may be secured in any suitable manner. Support 45 extends above the lamp 43 and is slidably supported by plate 37 by means of a bolt 46 secured to the plate 37 having a center opening therein. In 45 order that the outer lampholder 44 may be biased to hold a lamp in operative position, a threaded stud 47 is secured at the inner end of support 45 and extends through the center opening in bolt 46 and upon which a spring 48 is slidably located. Spring 48 is slightly compressed against plate 37 by means of a split member 49 which is held upon stud 47 by means of a nut 50 threadedly engaging stud 47 and abutting against member 49. An inverted J-shaped flexible conductor member 51 having its long arm firmly secured between the halves of 55 split member 49 and its short arm secured to the plate 37 in any suitable manner, such as a terminal screw 52 is provided to carry power to support 45. By this construction, it will be obvious that support 45 is biased toward the back of the housing 2 at all times to cause 60 the lampholder 44 to firmly engage the main terminals of the lamp 43. In order to replace lamp 43, support 45 need only be pulled toward the front of the housing 2 thereby causing the front lampholder 44 to be separated from the lamp 43, and then the lamp is freed for 65 removal. A high voltage terminal or ignition electrode 79 is provided centrally at one side of lamp 43 which extends laterally and beyond the envelope of lamp 43 in order that an ignition circuit 100, as subsequently described may be secured thereto in any suitable manner, such as by a solderless connector.

Referring to Figs. 2 and 5, wherein a blaze unit is shown, it will be noted that the housing 2 is identical in all respects to the housing already discussed with relation to the flash unit, and, accordingly, like reference numerals have been used. The blaze unit is adapted, how-

ever, to utilize a plurality of elongated discharge devices, such as gaseous tubes 60, which are arranged horizontally one above the other behind the lens 10 and supported by any suitable socket type lamp-holding means 270. As shown in Figs. 2 and 5, it will be noted that each lamp 60 is located adjacent the vertex of a trough-shaped reflector 271. Reflectors 271 are secured at their vertices by any suitable means, such as machine screws (not shown) to an insulating plate 54 which, in turn, is secured at each of its ends by any suitable means, such as bolts 55, to inwardly projecting lugs 53 integral with the housing 2. In order to provide for rigidity for the reflector 56 and in order that they may retain proper spacing with relation to each other, each reflector 271 is provided with a flat outwardly projecting flange 272 at each of its edges which overlaps the corresponding flange 272 of the adjacent reflector 271. Reflectors 271 may be formed of any suitable material such as aluminum or an aluminum alloy, which is capable of being processed to obtain a high reflecting surface. Also, in order to insulate the reflectors 271, from the housing 2, plate 54 is formed of any suitable insulating material, such as a phenolic insulating material.

In view of the fact that lamps 60 differ from lamp 43, a power unit 210 having different components than power unit 200 is located within the housing 2. Although not shown in the wiring diagrams, each housing 2 is provided with a door switch 59 adjacent the inner lower edge of each door 5 and 5' so that when any door 5 or 5' is open, the power supply to the power unit is interrupted.

As has been indicated, the power unit 200 for the flash unit is located within the housing 2 and comprises that part of the circuit shown in Fig. 4, which is bounded by the dot-dash outline. As shown, the electrical power for operating the flash unit is supplied from any suitable three-wire source 203 of alternating current. It should be noted, however, that if desired an individual unit may be operated from any suitable two-wire source rather than the three-wire source; however, when a plurality of such units are operated from a common source, a three-wire source is preferred in order to obtain a balancing of the load. Source 203 comprises two main power conductors 61 and 62 and a neutral conductor 63. The power unit 200 is selectively controlled as hereinafter described by means of a flash selector 202, ignition control 201, and a switch S1, which components may, if desired, be mounted within the housing 2 so as to be accessible from the outside of housing 2, whereby a flash unit can be controlled at its location. In keeping, however, with an approach lighting system, wherein it is desired to have a central control area, such controls are remotely located so that a plurality of light units may be operated from these controls at a central location and having individual control cables extending to the flash units.

As shown, the flash selector 202 comprises a rotary drum switch which is utilized to control various sections of the power unit 200; however, other types of standard control devices could be utilized for such purposes. Selector 202 is operable from an off-position through positions 1, 2, 3, 4 and 5, of which position No. 2 is the low intensity setting, position No. 5 is the high intensity setting and positions 1, 3 and 4 are provided to accomplish certain control functions as hereinafter described. The ignition control 201 is utilized to effect a flash operation of the flash unit at timed intervals, and, accordingly, a precision timer (not shown) is contained therein to accomplish such purpose. For a more detailed description of such a timer the above-identified copending application is again referred to.

Power unit 200 comprises a pair of condensers or condenser banks CF-1 and CF-2, with condenser CF-1 being connected in parallel across the main end electrodes 80 and 81 of the lamp 43. Condenser CF-2 is selectively

connectible in parallel with condenser CF-1 by means of a relay 84. Condensers CF-1 and CF-2 are alternately charged, and then discharged through the lamp 43 when its ignition electrode 79 is energized in response to the ignition control 201 as hereinafter explained. In addition to the condenser banks, the power unit 200 comprises a plurality of control relays 82, 83 and 84, a filament transformer TF2, a power transformer TF1, a pair of rectifier tubes 85 and 86, a pair of resistors RF1 and RF2, and a pair of potentiometers 87 and 88. The electrical energy for operating the lamp 43 as well as the control relays of the power unit is obtained from the supply circuit 203. Filament transformer TF2 has its secondary winding 89 connected to the filaments of the rectifier tubes in a well-known manner and the secondary winding 90 of the power transformer TF1 is connected to the plates of the tubes. The charging circuit for the condensers extends from the middle tap 91 on the secondary winding 90, through conductor 92, condenser CF1, conductors 93 and 94, contact members 84a, conductor 95, potentiometer 87 and resistor RF2 to the middle tap of the secondary winding 89 of the filament transformer TF2.

It will be noted in this instance that this is the charging circuit for both condensers CF-1 and CF-2 in parallel which is effective when relay 84 is deenergized as shown. In this position, contact 84b connects condenser CF2 in parallel with CF1. Contact members 84a when closed, as shown, shunt the potentiometer 88 and resistor RF1 from the charging circuit. This provides for increasing the charging current for the maximum capacitor connection. It will be apparent that when relay 84 opens its contact members, condenser CF2 will be disconnected and the potentiometer 88 and resistor RF1 rendered effective so as to increase the resistance of the charging circuit for the lower capacitor connection. As will be described hereinafter, the single capacitor CF1 is used for low intensity flashing operation and both capacitors for high intensity flashing operation.

Relay 83 functions to control the effectiveness of the discharge resistor RF3 connected across the capacitors, while relay 82 functions to render the ignition circuit controlled by the ignition control 201 effective. This circuit is closed by contact members 82a. Relay 82 also functions to energize the primary winding 96 of the power transformer TF1 through its contact members 82b.

Reference has been made to the operation of the lamps 43 by energizing their ignition electrodes 79. In order to provide a high frequency, high-voltage ignition voltage which may be impressed on the ignition electrode in response to the operation of the ignition control 201, each power unit also embodies an ignition circuit 100 which comprises a transformer 244 connected across supply conductors 62-63 for inducing a high voltage in its secondary. Such high voltage is utilized to charge a condenser 246 connected across the secondary until such charge is sufficient to cause a spark gap 248, connected in series with the secondary of transformer 244, to break down and conduct, thereby producing a surge through the primary of another transformer 250 connected in series with spark gap 248 and the secondary of transformer 244. Such surge through the primary of transformer 250 causes a higher voltage to be generated in the high-voltage secondary winding 101 of transformer 250 which is connected to the ignition electrode 79 as previously indicated and to ground. The operation of the power unit 200 is such that when lamp 43 is subjected to the proper operating voltage by the condensers and, when the ignition electrode 79 is energized, the lamp 43 is caused to discharge and flash. With such a lamp 43, as described, it is necessary to energize the ignition electrode 79 for each flash operation of the lamp.

In order to operate the flash unit, a switch S-1 must initially be closed which establishes a circuit for energizing the primary winding of the filament transformer TF2. This circuit extends from conductor 63 through switch

S-1, primary winding of TF2, conductor 133a, and conductor 133 to the distribution conductor 62. If desired, door switches 59 may be connected in series with switch S-1, to prevent energization of power unit 200 when either door 5 is open. As shown, all relays are in the deenergized position, and if a low flash operation is desired, the flash selector switch 65 is actuated from its off position through the No. 1 position to its No. 2 low position. On the intermediate No. 1 position, the control conductor for relay 84 is energized through a circuit from ground conductor 63, through contact members 134 and 135 of the selector switch 202, which are bridged by the connected movable segments 136 and 137, conductor 140, operating coil of relay 84 to distribution conductor 62. This effects the opening of relay 84 so as to disconnect condenser CF2 and increase the resistance of the charging circuit for condenser CF1 by rendering potentiometer 88 and its associated resistor RF1 effective, as described hereinbefore.

On position No. 2 of the selector switch 202, which is the low intensity flash position, an energizing circuit for relays 82 and 83 of the power supply unit is established. This circuit extends from conductor 63 through contact members 134 and 143 of the selector switch 202, which are bridged by the connected movable segments 136 and 141, conductor 144, and operating coils of relays 82 and 83 in parallel to distribution conductor 62. Relay 82 closes to energize the primary 96 of power transformer TF1 through its contact members 82b and also closes the ignition circuit referred to hereinafter at contact members 82a. Relay 83 operates to disconnect the discharge resistor RF3 from the condenser circuit at contact members 83a. It will, thus, be apparent that the unit is now ready for operation on low flash.

Assuming that it is desired to operate the flash units on high flash operation, the selector switch may be actuated through positions Nos. 3 and 4 to the high intensity position No. 5. On position No. 3, all of the relays which have been energized on the low intensity flashing operation with the exception of relay 84 are deenergized. On position No. 4, relay 84 is also deenergized and condenser CF2 is then connected in parallel with CF1, so as to increase the available capacity, and the charging circuit is recalibrated by shunting the potentiometer 88 and resistor RF1. This provides for subjecting the lamp 43 to a higher operating discharge current. On the high intensity position No. 5, relays 82 and 83 are again energized through the segment 145 of the selector switch 202, the relay 84 is deenergized as at positions No. 4 and 5. Upon energization, relays 82 and 83 again perform the same functions as before. Relay 82 closes the ignition circuit at contact members 82a and energizes the power transformer TF1 at contact members 82b. Relay 83 disconnects the discharge resistor RF3 at 83a.

In order to obtain ignition of lamps 43, electrode 79 is controlled through the ignition control 201 when the selector switch is at either position No. 2 or No. 5. Electrode 79 is energized through ignition circuit 100, which, in turn, is energized from conductor 63, by conductor 148b, control 201, conductor 148a, contacts 82a, the primary of transformer 244, conductor 133 to supply conductor 62. The exact method of timing of ignition control 201 is unimportant from the standpoint of a single flash unit; however, when a larger number of units are energized and a flash sequence is desired, such ignition control is of great importance and accordingly for such controls the above-identified case should be consulted. Such flash units will be operable at their maximum high intensity as long as selector switch 202 remains on position No. 5 and in accordance with the operation of ignition control 201.

Referring again to the condenser charging circuit, it will be noted that rectifier tubes 85 and 86 are connected so that the tubes conduct on alternate half cycles so as

to constitute a full-wave rectifier. Thus, over a period of time, a large charge will be placed upon the capacitors, which is discharged across the electrodes 80 and 81 of lamp 43 when lamp 43 is triggered by energizing its third electrode 79. When such triggering occurs, the voltage across the condenser falls to the voltage value across the plate and grid of the rectifier tube then conducting which is insufficient to maintain a discharge across the lamp 43. By utilizing rectifier tubes 85 and 86 so that the rectified half-wave voltage drops to substantially zero within one-half cycle after triggering, applicant is able to insure that only a flash discharge occurs across lamp 43. Further, when a plurality of such lighting units are used, separate rectifier tubes 85 and 86 for charging condensers CF-1 and CF-2 are located in each lighting unit. As rectifier tubes 85 and 86 conduct in one direction only, feed back from the charged condensers CF-1 and CF-2 in one unit is prevented and one unit will not have any electrical effect upon the other. It is, of course, obvious that the ignition of lamp 43 must be timed so as to occur after the condenser has had sufficient time to become charged.

As has also been indicated, the power circuit 210 for the blaze unit is located within its housing 2 and comprises the part of the circuit shown in Fig. 6, which is bounded by the dot-dash outline. As before, the electrical power for operating this unit is supplied from any suitable source 214 such as a three-wire system having two main conductors 56 and 58 and a neutral conductor 57. If desired, a two-wire system could be employed. The power unit 210 is selectively controlled as herein-after described by means of a selector 212, ignition control 211, and a switch S-2, which components may be mounted in the same manner as the similar components previously described.

As shown, selector 212 comprises a rotary drum switch which is utilized to control various sections of the power unit 210; however, other types of standard control device could be utilized for such purposes. Lamps 60 are adapted to be operated as either flashing units or steady burning, i.e., blaze units, and, accordingly, selector 212 provides a control for both types of operation. Selector 212 is operable for flash operation from an off position through positions 1, 2, 3, 4, and 5 of which position No. 2 is the low intensity setting, position No. 5 is the high intensity setting, and positions No. 1, No. 3, and No. 4 are provided to accomplish certain control functions. In the opposite direction, selector 212 is operable through positions Nos. 1 to 4 which is the blaze or steady operating direction. Position No. 2 is the low intensity position, No. 3 the medium intensity, No. 4 the high intensity, and No. 1 is for switching purposes. The ignition control 211 is utilized to energize lamps 60 and effect a flash operation thereof in a timed sequence, and, accordingly, a precision timer (not shown) is contained therein to accomplish such purposes.

The power unit 210 functions in generally the same way as a power unit 200 described in connection with the flash unit except that in this instance the lamps 60 are operated in two different ways, namely, flash and steady. Insofar as the flash operation is concerned, the elements and their manner of operation are generally the same. As shown, the six lamps 60 are connected in series circuit relation, and each lamp is provided with a cutout device 108 connected in parallel therewith to provide a shunt connection for the lamp in the event of failure thereof. In general, each unit 210 comprises a pair of rectifier tubes 109 and 110, a plurality of control relays 111, 112, 113, 114, 116 and 117, a power transformer TB1, a filament transformer TB2, potentiometers 118 and 119, and resistors RB1, RB2, RB3, and RB4. As in the case of power unit 200, the plates of tubes 109 and 110 are connected to the secondary winding of the power transformer TB1, and the filaments to the secondary winding of the filament transformer TB2. The

charging circuit for the condensers or condenser banks CB1 and CB2 extends from a middle tap 120 on the secondary winding of power transformer TB1 through contact members 116c, either condenser CB1 alone, or in parallel with CB2, depending upon the position of the relays 116 and 117, and either through both potentiometers 118 and 119 and resistors RB1 and RB2 in series or potentiometer 119 and resistor RB1 alone, depending upon the position of relay 117, to the middle tap 121 on the secondary winding of power transformer TB2.

As will be explained more in detail hereinafter, relay 116 is energized when the lamps 60 are being operated as flash lamps and closes the charging circuit at contact members 116c and condenser CB1 is effective. When relay 117 is deenergized, as shown, it connects the second condenser CB2 to the charging circuit in parallel with CB1 through contact members 117a. With contact members 117b closed and contact members 116g of relay 116 also closed, the potentiometer 118 and its associated resistor RB2 are shunted out of the charging circuit, so as to decrease the resistance thereof. When relay 117 is energized, condenser CB2 is disconnected, and the potentiometer 118 and resistor RB2 rendered effective to increase the resistance of the charging circuit on low intensity flash operation.

When the lamps 60 are operated as steady units, the condensers and their associated charging circuits are ineffective as relay 116 is deenergized. In this instance, the lamps are connected directly across the secondary winding of the power transformer TB1 through contact members 116a and 116f of the relay 116, which is the main control relay. When relay 116 is energized, this connection is interrupted, and the lamps are connected across the capacitors through contact members 116b. The charging circuit for the capacitors is closed through contact members 116c as explained hereinbefore. Contact members 116d and 116e control the connection of the discharge resistors RB3 and RB4 to the condensers. Relay 116 is also provided with other contact members 116h which close the ignition circuit or connection 123 to the lamps 60.

As in the case of the flash unit, each blaze unit embodies an ignition circuit having a transformer 124 connected across the supply conductors 57—58 for inducing a high voltage on a condenser 146 connected across its secondary. A spark gap 149 and the primary of another transformer 125 are connected across condenser 146 to obtain a high voltage surge through transformer 125 as previously discussed. The secondary of transformer 125 is connected between ground and the ignition connection 123 through contact members 116h. This ignition connection goes to the midpoint of the series-connected lamps, as shown.

When relay 116 is deenergized, as shown, the lamps 60 are connected for steady operation across the secondary winding 128 of the power transformer TB1, and its primary winding 129 is selectively connectible to the conductors 57 and 58 of the distribution circuit in a number of different ways by the operation of relays 112, 113, and 114. The final connection to the distribution circuit is made through contact members 111b of relay 111. This is the main energizing relay for the power supply unit. The contact members of the other control relays 112, 113, and 114 are so arranged and interconnected that, when relay 112 is energized and closed, as it is throughout the steady operation, relays 113 and 114 function to provide the necessary connections for the primary winding 129 to subject the lamps to the desired operating voltages. When relay 113 is closed, the primary winding 129 of power transformer TB1 is connected from conductor 57 and in series with the lower portion of reactor winding R, tap connection 131, and contact members 113b, 112a, and 111b to conductor 58. This provides the necessary secondary voltage for operating the lamps on high steady operation.

For the medium steady operation, relay 113 is open and relay 114 closed. This connects the primary winding 129 through the entire winding of reactor R and contact members 114b, 113a, 112a, and 111b. This provides the intermediate secondary voltage for medium steady operation. For low steady operation, relays 113 and 114 are both open, and the primary winding 129 is connected directly to conductors 57 and 58 through resistor R7 and contact members 114a, 113a, 112a, and 111b. This provides the necessary low secondary voltage. Power unit 210 also includes a third transformer TB3 and a condenser CB3 which is rendered effective for power factor correction when both relays 112 and 113 are energized and closed on high steady operation.

The operation of the blaze unit for flashing operation is generally the same as for the flash unit. When switch S-2 is closed, the primary of the filament transformer TB2 is energized from conductor 57 to distribution conductor 58. Door switches 59 may be connected in series with the primaries of transformers TB1 and TB2, to prevent energization of power unit 210 when either door 5 is open. Fig. 6 illustrates the condition of the circuit with the blaze selector switch 212 in the off position. It will be apparent that when the selector switch 212 is in the off position, a circuit is established which extends from conductor 57 through stationary contact members 153 and 155 bridged by the connected segments 150 and 151 to conductor 154, whereby an operating circuit for relay 112 is established to distribution conductor 58.

When relay 112 is closed, it performs a number of functions; at contact members 112b, it opens the power connection to the tap 130 of transformer TB1; it closes its contact members 112a to connect the entire primary winding 129 of power transformer TB1 to conductor 58; at contact members 112c, it partially closes the circuit to transformer TB3 from conductor 57. On flash position No. 1 of the selector switch 212, the operating circuit for relay 112 is deenergized and relay 112 opens. With relay 112 open, contacts 112d are closed, and the main control relay 116, which functions to set up the necessary connections to the lamps for flash operation, is energized from conductor 58, through contacts 112d, to conductor 57. Relay 116 at contacts 116b and 116c establishes the charging circuit for the condensers and connects the lamps across the condensers. Contact members 116a and 116f are opened so as to disconnect the lamps from the full secondary winding of the transformer TB1 which is the blaze or steady connection. Contact members 116e open to disconnect the condenser discharge resistors RB3 and RB4. Contact members 116g are also closed. It should be noted that relay 116 stays closed during the entire flashing operation.

On position No. 1, relay 117 is energized from conductor 57, segment 150 which is internally connected to segment 159, through stationary contact member 158, and conductor 161 to conductor 58. Relay 117 opens to disconnect condenser CB2 at contact members 117a and to increase the resistance of the charging circuit by opening contact members 117b to render potentiometer 118 and resistance RB2 effective.

When the selector 212 is actuated to the low flash position No. 2, relay 111 is energized from conductor 57, segment 150 of switch 212 which is internally connected to segment 168, through stationary contact element 167, and conductor 173 to conductor 58. Relay 112 continues to be deenergized as previously described. Upon the operation of relay 111, the ignition circuit is closed at contact members 111a; at contact members 111b, the energizing circuit for the power transformer TB1 is completed. The circuit extends from distribution conductor 58, through contact members 111b, 112b, tap 130, and a part of primary 129 to conductor 57. The power unit is now energized. When the ignition control 211 is operated, the blaze units are all being flashed at low intensity. The previous remarks regarding the igni-

11

tion control 201 of the flash unit are equally pertinent here and need not be repeated.

If it is desired to flash the blaze units at high intensity, the selector switch 212 may be operated through positions Nos. 3 and 4 to the high intensity position No. 5. At position No. 3, relay 111 is deenergized, but relay 117 is still held energized.

When the selector switch 212 is operated to position No. 4, relay 117 is also deenergized, and capacitor CB2 is connected into the circuit, and the relay also decreases the resistance of the charging circuit by shunting potentiometer 118 and resistance RB2 at contact members 117b. This switching operation is to condition the power supply unit for high intensity flashing.

At position No. 5, relay 111 is again picked up and performs the same operations as before to close the ignition circuit at contacts 111a and connect the transformer TB1 to the power source through contact members 111b. The system is now operating to flash the blaze units at high or maximum intensity. Thereafter, ignition control 211 is utilized, as before, to initiate the high intensity discharge.

When it is desired to operate the blaze units to produce a steady light, the selector switch 212 is returned to the off position, and the relay 112 is again energized through the contact segment 151 and closed. When relay 112 closes, it deenergizes through contacts 112d the main control relay 116 which, at its normally closed contact members 116a and 116f, connects the lamps 60 to the secondary winding of the power transformer TB1 for steady operation. In other words, the lamps are connected directly across the full secondary winding of the transformer. Other contact members 116b, 116c, and 116g of relay 116 disconnect the lamps from the condenser and charging circuit. It is to be noted that relay 112 remains energized and relay 116 remains deenergized throughout the steady operation, so as to maintain these connections.

At position No. 1 in the blaze or steady direction of operation of the selector switch 212, relay 117 is again energized from conductor 57, segment 150 of switch 212 which is internally connected to segment 170, through stationary contact member 158, through conductor 161 to conductor 58 which opens to disconnect condenser CB2 from the charging circuit.

On position No. 2, which is the low intensity steady position, relay 111 is energized from conductor 57, segment 150 of switch 212 which is internally connected to segment 174, through stationary contact member 167 of switch 212 through conductor 173 to conductor 58. Relay 111 remains energized throughout the blaze operation and at contact members 111b connects the primary winding 129 of power transformer TB1 to the distribution circuit. In this instance, since relay 112 is closed and relays 113 and 114 open, this primary winding is connected to conductors 57 and 58 through contact members 111b, 112a, 113a, 114a, and resistor R7. This provides the necessary secondary operating voltage for low intensity steady operation.

When the selector switch 212 is moved to position No. 3, which is the medium intensity steady position, all of the relays which were operated remain closed and, in addition, relay 114 is energized from conductor 57, segment 150 of switch 212 which is internally connected to segment 180, through stationary contact member 179 and conductor 182 to conductor 58. When contact members 114a are opened and 114b closed, the primary winding 129 of transformer TB1 is connected to the distribution conductors 57 and 58 through the full winding of reactor R. This provides the necessary secondary voltage for medium intensity steady operation.

When the selector switch 212 is operated to position No. 4, which is the high intensity steady position, the same relays remain operated, except that relay 114 is deenergized, and relay 113 is energized from conductor 57, seg-

12

ment 150 of switch 212 which is internally connected to segment 185, through stationary contact member 184, and conductor 187 to conductor 58. When relay 113 now closes, the primary winding 129 of transformer TB1 is connected to the source through the tap connection 131 of reactor R. This establishes the correct secondary voltage for the high intensity steady operation. At the same time, relay 113 through its contact members 113c completes the energizing circuit for transformer TB3 which was partially closed through contact members 112c. This renders the condenser CB3 effective for power factor correction.

While separate flashing operations of the flash and blaze units have been described, it will be apparent that a plurality of these units may be operated in unison, as described in the above-identified case. In view of the foregoing detailed description of a preferred embodiment of my invention, it will be apparent that I have provided a novel type of lighting system for facilitating the visual landing of aircraft under all weather conditions. The most important aspect of this invention is in the individual lighting units and in the use of individual power supply units in each type of unit which is entirely separated from similar units, whereby a flash of light may be obtained.

While a specific embodiment of my invention has been described, it is to be understood that the principles of the invention may be practiced in other ways. Thus, if desired, only single flash intensities could easily be obtained by simplifying the control components. Also, in the blaze unit, the flashing operation could easily be eliminated. Accordingly, the particular embodiment described is to be considered as illustrative only.

I claim as my invention:

35. 1. A light unit comprising a housing having mounted therein a reflector, lamp supporting means mounted in said reflector adapted to support a lamp having a pair of main terminals and a third ignition terminal, and a power supply unit mounted in said housing comprising a first circuit connected to capacitive means for charging the same including a condenser discharge resistance, said capacitive means being connected to the main terminals of said lamp supporting means, a second circuit connected to said third terminal, a first relay means for varying the capacitance of said capacitor means, a second relay means for disconnecting said discharge resistance from said first circuit, and a third relay means for energizing said first and second circuits from a source of power for causing a discharge across a lamp when inserted in said lamp supporting means.

40. 2. A light unit comprising a housing having mounted therein a reflector, lamp supporting means mounted in said reflector adapted to support a lamp having a pair of main terminals and a third ignition terminal, and a power supply unit mounted in said housing comprising a first circuit connected to capacitive means for charging the same, means for electrically connecting said capacitive means to lamp supporting means to discharge across said main terminals, a second circuit connected to said third terminal, a first relay means for varying the capacitance of said capacitive means, and a second relay means for energizing said first and second circuits from a source of power for causing a discharge across a lamp when inserted in said lamp supporting means.

45. 3. A light unit comprising a housing having mounted therein a reflector, lamp supporting means mounted in said reflector adapted to support a lamp having a pair of main terminals and a third ignition terminal, and a power supply unit mounted in said housing comprising a first circuit connected to capacitive means for charging the same including a condenser discharge resistance, said capacitive means being connected to the main terminals of said lamp supporting means, a second circuit connected to said third terminal, a first relay means for varying the capacitance of said capacitor means, a sec-

ond relay means for disconnecting said discharge resistance from said first circuit, and a third relay means for energizing said first and second circuits from a source of power for causing a discharge across a lamp when inserted in said lamp supporting means, and said second and third relays being electrically connected together so as to be operable simultaneously.

4. A light unit comprising a housing having mounted therein at least one lamp supporting means which is adapted to support a lamp, a power supply unit mounted in said housing comprising a plurality of energy storing means at least one of which is connected to said lamp supporting means, switching means for selectively connecting another of said energy storing means to said lamp supporting means, triggering means connected to said lamp for causing a discharge of said energy storing means connected to said lamp supporting means to occur across a lamp when mounted in said lamp supporting means, and means connected to said energy storing means for causing the voltage of said energy storing means to drop to a value below the voltage which will sustain a discharge across said lamp after said energy storing means has been discharged.

5. A light unit comprising a housing having an opening therein, a plurality of elongated reflectors contiguously mounted within said housing behind said opening in a plane approximately parallel thereto, lamp supporting means mounted within said housing to support a lamp in each of said reflectors, respectively, means for electrically connecting said lamp supporting means to each other, a power supply unit mounted in said housing comprising a first energy storing means connected across said lamp supporting means, a second energy storing means, switching means for connecting said second energy storing means across said lamp supporting means, means adapted to be connected to said lamp for causing a discharge of said energy storing means across a plurality of lamps when mounted in said lamp supporting means, and means connected to said energy storing means for causing the voltage therein to drop to a value below the voltage which will sustain a discharge across said lamps after said energy storing means has been discharged.

6. A light unit comprising a housing having at least one reflector mounted therein, lamp supporting means mounted in said housing to support a lamp in fixed relationship with respect to said reflector, a power supply unit mounted in said housing comprising a transformer having its secondary connected across said lamp supporting means, said transformer having a primary for controlling the energization of said secondary and adapted to be connected to an alternating current source, a plurality of impedances connected in parallel in the connection of said source to said primary, and switching means in each of said parallel connection so that the excitation level of said primary may be selectively varied.

7. A light unit comprising a housing having at least one reflector mounted therein, lamp supporting means mounted in said housing so as to be adapted to support a lamp within said reflector, a power supply unit mounted in said housing comprising a transformer having its secondary connected across said lamp supporting means, said transformer having a primary which is adapted to be connected to a source of power for controlling the energization of said secondary, a parallel connected resistor and reactor connected in series with said primary for controlling the excitation thereof, and switching means in each branch of said parallel circuit so that the excitation of said primary may be varied.

8. A light unit comprising a tubular housing having movable covers for covering each of its ends, and enlarged dish-shaped reflector, means on said housing engageable with said reflector for supporting said reflector with its open end facing one of said ends of said housing

and so that its apex extends inwardly of said housing, an insulating support extending inwardly from one inner surface of said housing so as to engage the outer side of said apex, a rigid first lamp holding means extending through said apex portion of said reflector and said support, a second lamp holding means movably secured to said support which extends inwardly of said reflector so as to be spaced from said first lamp holding means in a manner to support a gaseous discharge device therebetween, means connected to said support for biasing said second lamp holding means toward said first lamp holding means, a power supply unit secured to the inner surface of said housing so as to be located at least in part between said reflector and the last-mentioned inner surface, and means for electrically connecting said power supply unit to said lamp holding means.

9. A light unit comprising a housing having an opening therein, at least one reflector mounted within said housing behind said opening, lamp supporting means mounted in said housing to support a lamp in fixed relationship with respect to said reflector, a power supply unit mounted in said housing having two control circuits for controlling energization of said lamp supporting means, a first switching means for selecting either of said control circuits so that said control circuits are adapted to be energized from a source of electrical energy, one of said control circuits comprising a plurality of energy storing means at least one of which is connected to said lamp supporting means, a second switching means for selectively connecting another of said energy storing means to said lamp supporting means, means connected to said lamp supporting means for causing a discharge of said energy storing means, means connected to said energy storing means for causing the voltage therein to drop to a value below the voltage which will sustain a discharge across said lamps, the other of said control circuits comprising a transformer having a secondary connected across said lamp supporting means, said transformer having a primary for controlling the energization of said secondary, a plurality of control means connected to said primary for varying the excitation thereof, and a third switching means connected to each of said control means so that the excitation of said primary may be varied.

10. A self-contained light unit for use at airports and the like as an aid to airplane landing operations and the like, comprising, a reflector housing having a transparent front cover, a reflector mounted in said housing behind the front cover, lamp supporting means adapted to support a high-intensity discharge lamp having main terminals and an igniter terminal mounted within the reflector, a power supply unit mounted within the housing and electrically connected to the lamp supporting means and said igniter terminal, said power supply unit having input terminals adapted to be energized from an alternating current power source and including means for converting such alternating current to a pulsating direct current, energy storing means supplied with said pulsating current, means connecting said energy storing means to said lamp supporting means so that said energy storing means can discharge across the main terminals of said lamp, and means including a separate and direct connection of said source to the igniter terminal of said lamp supporting means including voltage step-up means for supplying a relatively high voltage to said igniter terminal.

11. A self-contained light unit for use at airports and the like as an aid to airplane landing operations and the like, comprising, a reflector housing having a transparent front cover, a reflector mounted in said housing behind the front cover, lamp supporting means adapted to support a high-intensity discharge lamp having main terminals and an igniter terminal mounted within the reflector, a power supply unit mounted within the housing and electrically connected to the lamp supporting means and said igniter terminal, said power supply unit having input

15

terminals adapted to be energized from an alternating current power source and including means for converting such alternating current to a pulsating direct current, energy storing means supplied with said pulsating current, means connecting said energy storing means to said lamp supporting means so that said energy storing means can discharge across the main terminals of said lamp, means including a separate and direct connection of said source to the igniter terminal of said lamp supporting means including voltage step-up means for supplying a relatively high voltage to said igniter terminal, and separate relay means in the circuits to said main and igniter

16

terminal means, respectively, and individual control supply conductors for said relays.
